UNITED STATES PATENT OFFICE.

EMILE BUENO, OF HERICOURT, FRANCE.

ELECTRICALLY-CONTROLLED REPRODUCING SCRIBER.

Application filed March 3, 1922, Serial No. 540,809, and in France March 11, 1921.

This invention relates to an apparatus to reproduce on paper and in their colors images autochrome, omnicolor and such like plates.

5 The object of my invention is to provide an apparatus that can be constructed of any size and will allow to be reproduced on paper, in their colors, in any number, and, photographically speaking in an unalterable 10 manner, images obtained on autochrome, omnicolor, dioptrichrome or such like plates.

In the drawings appended hereto:

Fig. 1 is a plan view of the apparatus.

Fig. 2 is an elevation of the same.

15 Fig. 3 is a detail in elevation illustrating the reproducer tracer.

Fig. 4 is a diagrammatic view of the electrical connections when arranged in parallel.

Fig. 5 is a similar view of the electrical 20 connections when arranged in series.

Fig. 6 is a sectional view of the negative holder.

25 The improved apparatus as shown in the preferred form in the accompanying drawings, includes a base E, from which rises a standard G having an upper portion overlying and in spaced parallel relation to the base E. This latter portion of the upright supports a cross piece B substantially centrally of the base and arms A, four in number, radiate from this cross piece B.

30 Slidably mounted on each arm, is a carriage H, and these carriages have projecting portions interiorly threaded to receive screw rods I'. The inner end of each of the screw rods is rotatably mounted in a support M rising from the adjacent arm A, the screw rod being extended inwardly beyond the support in the form of a shaft which is terminally provided with a pinion I. As the 35 screw rods I' are mounted for rotation but held against endwise movement, operations of the pinions will cause the carriages to be moved lengthwise the arms A. Rubber discs

40 T and V are arranged on the screw rods I' at the respective limits of travel of the carriage. One of the carriages supports a tracer K carrying a very fine needle 1 supported and manually adjustable through conventional means 2 in a spring blade 3. The blade is adjustable relative to the support for the tracer as a whole through screw 4, and a spring strip 5 overlies the blade 3 and is adjustable relative thereto by a set screw 6. The spring strip 5 and blade 3

carry carbon contact points 7, these points being of course adjustable through the set screw 6. By means of the set screw 4, the amplitude of vibrations of the needle 1 may be controlled to permit soft or contrasted proofs to be obtained. Upon contact with the reliefs the tracer vibrates making the microphonic carbon vibrate, which, being in the circuit of the style reproducers, make the potential of these circuits vary proportionately to the relief. The remaining carriages H are each provided with reproducers L (Fig. 3) in which the needle 8 is adjustably mounted through set screw 9 carried by an armature 10 of electromagnets 11.

70 A circular plate C is rotatably supported on the base through the medium of a post D tapered at its lower end for rotative support in a socket in the base, the upper end of the support passing through the cross piece B, said post above the cross piece being in the form of a worm J which simultaneously engages all of the pinions I and operates said pinions in the rotation of the plate C. Post D and therefore the plate C is driven by 75 means of a motor F, which may be of spring type through gearing 12, this motor being mounted for sliding movement on the base E by means of guides 13, and held in adjusted position in the base through the medium of an adjusting screw X.

80 On the upper portion of the standard G are arranged two microscopes, one of which as N is stationary, and the other of which as O is slidably adjustable by means of set screw 14. These microscopes immediately overlie the plate C and are adapted for focusing in the usual manner, the lower ends of each microscope having the crossed centering lines, as clearly shown in Fig. 1.

95 The plate C is provided with a negative holder, comprising a recess into which is fitted a frame 15 capable of limited adjustment radially of the disc by adjusting screws 16. Within the frame 15 is fitted a second frame 17 adapted for adjustment at right angles to the adjustment of frame 15 by screw 18, and within the frame 17 is arranged a negative holding frame 19, the meeting edges of frames 17 and 19 being on 100 curved lines 20 to permit a limited rotative adjustment of the negative frame through the medium of screw 21. Thus, the negative when in position may be adjusted in 105 practically all directions to a limited extent.

Wedges 22 are arranged to hold the negative within the frame 19 and also frame 19 in its adjusted position relative to the frame 17. Wooden or brass rectangular plates of the inner size of the negative holder, are set into the plate C to provide with the negative holder diametrically opposed pairs of operating surfaces.

10 A socket or other connector P provides for the application of current, the circuit being led through the respective tracers and reproducers in the manner indicated in the drawings. A switch S is provided in the circuit and automatically cuts off the current 15 when the negative has passed beyond the reach of the tracer.

Supposing a 4 x 6 centimeters autochrome plate is to be reproduced in its colors, I first, in the middle of its longer edges and on the 20 emulsified side, bare the glass by scratching off the gelatine on a 4 x 4 millimeters area.

I stick on this area a gelatine film of same size crossed in its middle by two reference lines similar to and of same thickness as 25 those of the microscopes.

Said autochrome having thus been prepared I print, by means of panchromatic plates, three monochrome negatives according to known principles, it will be apparent 30 therefore that the first one, obtained under an orange screen, will show blue in its transparent parts, the second, under a green screen, will show red, and the third, under a violet screen, will show yellow.

35 I then take three glasses of suitable thickness but perfectly plane, coated with a thin layer of 3% potassium bichromated gelatine, I expose during a suitable time each glass to each one of the monochromes; I then 40 treat them together with hot water as in pigment processes, and so obtain three new monochrome negatives in relieveo. Such relieveos will correspond respectively to blue, red and yellow.

45 The reference marks of those three monochromes would be rather difficult to see. In order to make them very plainly visible, I dip edgewise the two longer sides of each glass into a basin covered four millimeters 50 deep with the following solution:

	Grams.
Boiling distilled water	120
Iodide of potassium	1.6
Bromide of potassium	9

55 Before using it I wait until the solution has completely cooled down.

I then dip the edges again, exactly as before, into

	Grams.
Distilled water	100
Nitrate of silver	50

60 I end by a third operation, always proceeding in the same manner, but using a common revealer. The reference lines then

appear in black visible through the microscope. After drying the glass plates are ready for use.

In using them, I first put a plate-glass, say the blue one, in the negative-holder, I 70 clinch it with wedges and then make its reference marks register with those of the microscopes by operating the intermediate devices of the negative holder and the micrometric screw of mobile microscope O. 75

I then secure three sheets of paper, well stretched by means of thumb tacks on rectangular plates R which they out pass slightly. These three copy-sheets will receive the 80 image in colors.

I next cover the plates with three other sheets of blue paper, so called tracing paper, leaving a blue print under pressure. These three sheets are also to be well stretched and secured with thumb-tacks. 85

I then operate the large micrometric screw of explorer tracer K so that the tracer will just skim the relief surface of the glass.

I operate likewise the micrometric screws of reproducer tracers L, so that when the 90 electric current is switched on, the needles of said tracers will suitably press on the tracing paper.

I put the plug into the jack, such plug being connected with a small pile or battery 95 of suitable power.

I next wind up the clockwork, which imparts its movement by means of one of the outer pinions of the box, driving the gear of the mobile plate axle. Mobile plate C begins to rotate, bringing the relief monochrome negative under explorer tracer K, and the rectangular plates R, together with the sheets that cover them, under reproducer tracers L. At this moment the carbon 100 of the switch comes into contact with the mass. At each relieveo corresponding to the blues, violets and greens of the autochrome, the monochrome lifts the needle of explorer tracer K in the proportion in which blue 105 enters into the composition of those colors, thus acting on the microphone carbon which modifies the current in ratio to the intensities of the relieveo. The current being thus modified, reproducer tracers L will faithfully reproduce in blue the current modifications, giving a blue-image. 110

Once the blue image obtained, I substitute for the blue monochrome relieveo the red one and make the reference marks register with those of the microscopes, but, this time, without interfering with the latter, only the intermediate devices having to be operated. When the registering is achieved I substitute to the blue tracing paper a red one 120 without touching the copy sheet. 125

I displace the clockwork by operating the box-outcentering knurled stud X. I wind up the clock and the operation begins again. The plate then revolves in the opposite di- 130

rection. A red proof is thus grafted on the blue one.

I finish by repeating the operation with the yellow monochrome relieveo and with 5 yellow tracing paper. Proofs so obtained will reproduce all the colors of the autochrome.

Instead of using tracing paper, I may sprinkle with very finely powdered pastel 10 or crayon the surface of the copy-sheets. Obviously the color of the crayon must correspond to the color of the tracing paper replaced thereby. Care should be taken to remove delicately the crayon with a very fine 15 badger-hair brush.

If from three trichrome selected negatives issued from one and the same autochrome, three corresponding monochromes are obtained in relieveo by the bichromated gelatine 20 pigment process and after such negatives have been perfectly registered respecting one another, the blue one is selected and placed in the apparatus and its reference marks having been registered with those of the 25 microscopes, the apparatus is set in motion, the explorer tracer will, on contact with the relieveos, cause to be vibrated a microphonic carbon varying the electric current which energizes the electro-magnet with which the 30 other tracers, so-called reproducers, are provided, and said reproducer tracers will trace in blue crayon the current variations, making thereby a blue part image.

To substitute for the blue relieveo monochrome the red one, the latter has to be put exactly in the same place and to do so the microscopes must not be interfered with while the reference marks have to be made to register. Leaving the copy-sheets as they 40 are red crayon is sprinkled on instead of blue crayon. The apparatus is then set going again and hereby a red image grafted on the blue one. By this second operation a blue, red, violet image is obtained. The operation is repeated for yellow with yellow 45 crayon, and all the colors are thus obtained.

Instead of crayon a sheet of correspondingly colored tracing paper may be used.

I claim:

50 1. An apparatus to reproduce on paper and in their colors images from autochrome, omnicolor, dioptrichrome and like plates, comprising a circular plate, said plate being formed with opposed pairs of defined spaces to receive the negative and the respective 55 monochrome negatives, and a plurality of tracers movable radially of said plate, and means whereby the position of the monochrome negatives in relieveo may be successively set in registry with the position of the initial monochrome negative in relieveo.

60 2. An apparatus to reproduce on paper and in their colors images from autochrome, omnicolor, dioptrichrome and like plates, comprising a circular plate, said plate be-

ing formed with opposed pairs of defined spaces to receive the negative and the respective monochrome negatives, and a plurality of tracers movable radially of said plate, and microscopes whereby the position 70 of the monochrome negatives in relieveo may be successively set in registry with the position of the initial monochrome negative in relieveo.

3. An apparatus of the class described, 75 comprising a circular plate, means for rotating said plate, said plate being formed with opposed pairs of defined spaces to receive the negative and the respective monochrome negatives, a tracer movable radially of the plate, 80 and reproducers movable radially of the plate in exact correspondance with the movement of the tracer.

4. An apparatus of the class described, 85 comprising a plate mounted for rotation about an axis, a tracer supported above the plate and movable radially thereof, reproducers supported above the plate, means for electrically controlling said reproducers by the tracer, means for moving said reproducers radially of the plate in exact correspond- 90 ence with the movement of the tracer, and means for rotating the plate, said plate being formed with a negative holder capable of limited adjustment in all directions with 95 which the tracer is to cooperate, said plate being further formed with particular surfaces with which the respective reproducers cooperate during movement of the tracer with relation to the negative. 100

5. An apparatus of the class described, comprising a base, a negative holding plate mounted for rotation thereon, arms supported above the plate and extending radially thereof, carriages mounted on the arms 105 for longitudinal adjustment thereon, threaded rods having threaded connection with the carriages for simultaneously adjusting the same, means for rotating the plate, and means operated by the movement of the 110 plate to simultaneously operate all of said threaded rods.

6. An apparatus of the class described, 115 comprising a base, a negative holding plate mounted for rotation thereon, arms sup- 120 ported above the plate and extending radially thereof, carriages, mounted on the arms for longitudinal movement, threaded rods having threaded connection with the carriages for simultaneously adjusting the 125 same, means for rotating the plate and means operated in the movement of the plate to simultaneously operate all of said threaded rods, a tracer movable with one of said carriages, and a reproducer movable with each of the other of said carriages.

In testimony whereof I affixed my signature.

EMILE BUENO.
